(57) **CLAIM**

The ornamental design for a display screen with transitional graphical user interface as shown and described.

DESCRIPTION

the patent or application file contains at least one drawing executed in color. copies of this patent or patent application publication with color drawing(s) will be provided by the office upon request and payment of the necessary fee.

1. display screen with transitional graphical user interface

1.1: front

1.2: front is a second view in the sequence

1.3: front is a third view in the sequence

the outermost broken lines in the reproductions show a display screen or portion thereof, and form no part of the claimed designs; the other broken lines shown in the reproductions 1.1, 1.2 and 1.3 form no part of the claimed design. the appearance of the graphical user interface transitions sequentially between the reproductions 1.1-1.3; the process or period in which one image transitions to another forms no part of the claimed design.

1 Claim, 3 Drawing Sheets
